ABSTRACT OF THE DISCLOSURE

Straw plate for a piece of furniture such as a chair, made of as many free units as the pattern of the straw work desired necessitates, each unit being covered with coating fibre, adequate means being provided for the assembly of the covered units between them, which allows to get rid of the manpower required for usual straw work in which covering fibres interlace, while a similar appearance of the chair plate is obtained when finished, said plate being self-bearing.

The invention relates to a plate to be fitted on straw-bottomed chairs which can be made automatically thus doing away with the usual long manual work required for the covering or the re-covering with straw.

As a matter of fact, prior straw plates are covered with an interlacing of plant fibres joined in a continuous way. The chair plate has the appearance of a frame the center part of which is empty; the appearance of the outer side is obtained, at the same time the central part of the frame is filled-up, by this interlacing of fibre which takes a long time to make.

FIG. 1 shows a chair plate made according to the usual hand process.

Fibres A interlace with other fibres B, the latter being arranged on a plane at a right angle towards the others; the interlacing forms two diagonals C and D which give to the seat its concave shape. The interlacing of fibres according to the drawing shown on FIG. 1 is the most usual, but different other geometric designs can be obtained depending on the shaping used.

When the interlacing is too flat, upholstering is employed in order to puff-out the seat.

This handicraft process requires an extremely skilled manpower.

Moreover, the achievement of the bottom part of a seat plates takes approximately 3 or 4 hours.

The object of the invention is to overcome the inconveniences arising from this handicraft work and relates, to this end, to a straw plate for a piece of furniture, such as a chair, in which said plate is made of several units covered separately in such way that, when grouped together, said units reproduce the final aspect of the plate desired.

Each unit includes fastening parts which work with fastening parts rigidly locked with contiguous units.

A chair straw plate, according to the invention, is shown as a nonrestricted example, on the attached drawings in which:

FIG. 2 shows a top view of the seat plate made from various units according to the invention, said units being not yet covered with straw.

FIG. 3 shows a cross-section view along the line J—J in FIG. 2 of a unit fitted with struts, according to the invention.

FIG. 4 shows a view along the line G—G in FIG. 2, front units being removed.

2

FIG. 5 shows a view in perspective of the detail of an assembly of corners of two solid units.

FIG. 6 shows the various units partly completed which form the plate of a seat, according to another making process.

FIG. 7 shows another making process for the manufacture of the plate units in a single mechanic operation.

FIG. 8 shows another process for the covering of the plate units, according to the drawing of FIG. 7.

10 A straw plate of a seat, according to FIG. 2, is composed of an assembly of four separate units 1, 2, 3, 4 not covered with straw.

These separate units 1, 2, 3, 4 which have a triangular shape, approximately, are composed of an external frame, 15 the hollow central part of which is so designed that units 1, 3 and 4, or the central part fitted with struts 2a, 3a at right angles, will form a square which stiffens the rigidity of this unit.

The triangular frame of units 1, 2, 3, 4 includes a rim 20 2c, as this is shown for unit 2, which is approximately at a right angle with the surface of the unit and has the shape of the cog serrated edge of the unit.

This rim increases the rigidity of the assembly. It includes swells intended for the housing of fastening parts 25 3e, such as screws, pegs or similar pieces, working with tightening parts such as nuts or similar pieces held by corresponding swells of the contiguous edges of the abutting units.

According to a construction detail shown on FIGS. 2, 30 3 and 4, the assembly of various separate units 1, 2, 3 and 4 is obtained by the assembly in corners 5, 6, 7 and 8 and by a central assembly 9.

The corner assembly is made by interlocking two male and female moulded parts 10 and 11.

35 Male part 10 is, for instance, set at the various corresponding corners of units 1, 2, 3, 4, while the female part 11 is rigidly locked with the other corners of the base of the triangular units 1, 2, 3, 4, in such way that alternately, male unit 10 of a unit interlocks with female unit 11 of the adjacent corner of the abutting unit.

According to the construction detail shown on FIGS. 2 and 3, male parts 10 are rigidly fastened with the corners of straw units 2 and 4, while female units 11 are rigidly fastened with the corners of straw units 1 and 3.

40 45 This assembly by interlocking of two units 10 and 11, in shape of a case, imitates the wood corners of the straw plates of chairs made according to handicraft processes.

Such assemblies made with cases, allow the maker to reduce considerably the quantity of material used by 50 comparison with a solid parts assembly 12, 13 as shown on FIG. 4, while they give an impression of a certain volume.

Moreover, such type of assembly, owing to the use of male 10 and female 11 units, is stiff enough to allow the 55 fastening of a plate on the corresponding bearing points of the seat.

When assembling the various units 1, 2, 3, 4 by cases 5, 6, 7, 8 placed at the corners of the various bases, interjacent fastening units 1d, 2e, 2d, 1e . . . can be left out and replaced by a single central assembly 9 made, for instance, by the using of a groove 9a into which is set a split ring 9b.

60 It is obvious that central assembly 9 may be as well composed of an assembly including screws, hooks, or any other means of assembly, fastening for instance the corners of the units to a central small plate.

However, an assembly made with cases 5, 6, 7 arranged on the circumference of the seat, and with a central assembly 9, increases the flexibility of the plate and, consequently, the comfort of such seat.

65 70 In fact, various units 1, 2, 3, 4 can work freely between them.

3

The assembly obtained by using fastening parts **1d**, **1e**, **2d**, **2e**, etc. between the adjacent sides of the various units increases the stiffness of such a seat plate and, consequently, makes it less comfortable.

However, when such a type of assembly is used (which necessitates an assembly at the corners, either through cases **5**, **6**, **7**, **8** or through any other means) the thickness of walls **2c** can be reduced, so as to increase flexibility, and the latter method allows the maker to bring down the weight of the material used and, as a consequence, the cost price of the plate.

According to a different process, units **1**, **2** and **4**, shown on FIG. 2, are composed of a frame having a shape approximately triangular and are not fitted with struts **2a** and **3a** as unit **2** is.

Thus, it is possible to fill the empty part of units **3**, **4** with a flexible material, such as rubber, synthetic foam, or any other, which increases the swelling of units **1**, **3**, **4** when covered with fibres and, as a result, improves the comfort of the seat.

FIG. 4 shows in detail the various types of assembly between the two adjacent units **1** and **4**, by means of male and female cases **10** and **11**, and of a central assembling part **9** made of a groove **9a** and a ring **9b**.

Owing to the fact ring **9b** is split, a spring effect or an additional elasticity is obtained which is materialized by the spacing between the adjacent sides of units **1** and **4**.

In order to simplify the scheme, units **1** and **4** of FIG. 4 do not include cog or serrated edges allowing the holding of the fibres in the right position.

As shown with thin lines on FIG. 2, units **1** and **4** include three strands of fibres **12** which allow the maker to see their marks in the part close to the center, as well as their fastening in the notches made in the edges of the respective units.

According to a simplified process and, as shown on FIG. 6, separate units **21**, **22**, **23**, and **24** are grouped together on a bearing plate **20**.

According to the process, the central strand, which is made of straw fibres, is replaced by a central strand prefabricated or moulded, made of wood, plastics, foam or any conglomerate.

The scheme which appears on FIG. 2 is not restricted and the visible plate may be cut out (when coated with fibre) according to the geometric pattern desired.

Each triangle, required for the making-up of a visible plate, is then covered separately with straw fibres (or with a synthetic thread), in such way that, when completed, each triangle appears like those shown under marks **21** and **24**; triangle shown under mark **23** is re-covered with a flexible synthetic material **25**, which there again gives the right softness to the seat plate. This flexible material **25** may be glued, stapled, or merely laid on the plate, the re-covering with straw fibres, made afterwards, securing it once for ever.

The triangle **22** is partially covered with straw fibre. The inclined sides of each triangle are cut away at **26** in order to secure the covering of plant fibres.

These four separate units are brought close to each other and fastened by any means on the plate support **20**; the whole assembly has then the appearance of usual seat plates.

In the case a plate delimited by an X and having four triangles is desired, two of these triangles **27** and **28** must be superposed and spaced by battens **29**. The covering with plant or synthetic fibres **30** is made automatically. Once these two units are covered, the fibre is cut off, for instance, along the axis line shown at **31**, so as to separate unit **27** from unit **28**.

Before doing this, fibres must be glued together, of course, as well as the surfaces and the sides of the two units.

Once these two units are separated, their interlocking is then carried out on the support plate **32** which shows on its surface recesses or grooves **33** in which will be

4

nested the rims **34** of the units **27** and **28** which serve to form the visible side of the seat plate. The straw, or other material, is then finally secured by this interlocking.

The invention is not restricted, of course, to the design examples hereinabove described and presented, from which other methods and processes can be used which remain within the scope of the invention.

What I claim is:

1. A straw plate construction for a furniture seat comprising
  - a plurality of approximately triangular separate plate units disposed in narrowly-spaced adjoining relationship defining a quadrilateral structure having base edges and base corners facing outward and apex edges and apex corners facing inward toward one another,
  - each unit including an approximately triangular body with a cover of cord-like material disposed thereon in courses arranged in side-by-side abutting engagement with one another,
  - means for coupling to one another the base corners of adjacent units,
  - and means for interconnecting the apex portions of said units.
2. A straw plate construction, according to claim 1, wherein each body includes an open-centered frame with said cover extending thereacross.
3. A straw plate construction, according to claim 1, wherein said apex edges have cutaway portions extending therealong and wherein said courses of said cord-like material are disposed in said cutaway portions.
4. A straw plate construction, according to claim 1, wherein said base edges have serrations forming notches therein and wherein said courses of said cord-like material are disposed in said notches.
5. A straw plate construction, according to claim 1, wherein said courses of said cord-like material extend entirely around each body.
6. A straw plate construction, according to claim 1, wherein said bodies have sides disposed transversely thereto along said edges and wherein said courses of said cord-like material extend across the upper surface of said body and downward along said sides of said body and terminate near the lower edges of said sides of said body.
7. A straw plate construction, according to claim 6, wherein there is provided a quadrilateral support plate with recesses therein receiving said sides of said bodies.
8. A straw plate construction, according to claim 1, wherein said coupling means includes a pair of interfitting coupling elements with one element secured to one base corner of each body and the other element secured to the adjacent base corner of an adjacent body.
9. A straw plate construction, according to claim 2, wherein reinforcing struts are connected to said bodies and extend across the open centers thereof.
10. A straw plate construction, according to claim 1, wherein said interconnecting means include aligned arcuate grooves disposed in said bodies adjacent the apex corners thereof and also include an annular connecting element seated in said grooves in interconnecting relationship with said apex corners of said bodies.
11. A straw plate construction, according to claim 1, wherein said interconnecting means also include fasteners extending across the spaces between adjacent units and entering into penetrating engagement with said adjacent units.
12. A straw plate construction, according to claim 1, wherein each pair of said triangular units are severed from a box-like structure including a pair of triangular bodies disposed in spaced parallel relationship with spacers extending therebetween and with the cover of cord-like material extending around the outer surfaces of both bodies and across the space therebetween.
13. A furniture plate construction such as a chair plate

of the type having a support covered by a cord of natural or synthetic material forming a particular final design on the visible surface of the plate, characterized in that the plate is composed of as many separate elements as the particular design is to contain, each of these elements being constructed of rigid material and covered individually and separately from one another by a flexible cord wound therearound, these covered elements being joined side-by-side in a particular arrangement forming said final design.

14. A furniture plate construction, according to claim 13, characterized in that each element, prior to its being mounted side by side with other identical or different elements, contains on its periphery notches receiving and guiding the wound cord.

15. A furniture straw plate construction, according to claim 13, characterized in that each element on its lower side carries means for connecting said elements to one another in said particular arrangement.

16. A furniture plate construction, according to claim 13, characterized in that the separate elements in said

particular arrangement are in general form of triangles joined to one another at their apexes and also at the ends of their bases.

17. A furniture plate construction, according to claim 13, characterized in that each element on its lower side has projections thereon, that in said particular arrangement said projections form a circular groove, and that a ring is disposed in said circular groove and interconnects said elements.

18. A furniture plate construction, according to claim 13, characterized in that an assembling board joins the separate elements side-by-side in said particular arrangement.
